United States Patent Office

Des. 194,099
Patented Nov. 20, 1962

194,099

WHEEL

Frank T. Walsh, Palo Alto, Calif., assignor to Go-Power
Corporation, Palo Alto, Calif., a corporation of Cali-
fornia

Filed Dec. 19, 1960, Ser. No. 63,255

Term of patent 14 years

(Cl. D14—30)

FIG. 2

FIG. 2

FIG. 3

FIG. 4

FIGURE 1 is a front perspective view of a wheel showing my new design;

FIGURE 2 is a rear elevational view of the wheel of FIG. 1;

FIGURE 3 is a cross-sectional view of the wheel taken along line 3—3; and

FIGURE 4 is a cross-sectional view of the wheel taken along line 4—4.

The tire shown in broken lines is included for illustrative purposes only.

I claim:

The ornamental design for a wheel, substantially as shown and described.
